AUTOMATIC TRAIN CONTROL SYSTEM FOR RAILROADS

Filed Dec. 4, 1925

James A. Peabody, Inventor

By Neil S. Weston,
his Attorney

UNITED STATES PATENT OFFICE

JAMES A. PEABODY, OF EVANSTON, ILLINOIS, ASSIGNOR TO GENERAL RAILWAY SIGNAL COMPANY

AUTOMATIC TRAIN-CONTROL SYSTEM FOR RAILROADS

Application filed December 4, 1925. Serial No. 73,177.

This invention relates to automatic train control, and more particularly concerns the operation of vehicles which are not provided with train control apparatus over railway systems including sections of trackway which are equipped for train control operation.

In applying automatic train control to railway systems, the entire trackway of the 10 system is not ordinarily equipped for train control operation, the protection afforded by the automatic control being found most desirable on the main line trackway where traffic conditions are congested. For this 15 reason, branch lines, sidings, and other sections of trackway are often unequipped for train control operation. In the operation of trains on a railway system having only certain portions of its trackway provided 20 with train control apparatus, it is found that certain trains, notably trains operating for the most part on branch lines, will travel for comparatively short distances only, over trackway sections which are 25 equipped for train control operation and over which equipped trains are being operated.

It is desirable to maintain at least a certain degree of automatic control over all 30 trains which operate over equipped sections and trackway, so that the control conditions may be uniform. In other words, it is not considered good practice to permit one train to travel over a given trackway 35 section without automatic control of any kind, while operating other trains over the same section under the protection of full automatic control. On the other hand, since the car-carried control equipment employed 40 on locomotives equipped for full automatic control involves a considerable investment and requires certain maintenance, it is obviously uneconomical to provide full automatic control equipment on a vehicle which can obtain the benefit and protection of automatic control for only a small portion of its 45 total operating distance.

With the above and other considerations in mind, it is proposed in accordance with 50 the present invention to provide simple and

inexpensive car-carried equipment for use on locomotives or other vehicles which travel for the most part over unequipped trackway, which system will give a certain degree of control or automatic protection while trackway sections which are equipped for train control operation are being traversed. More specifically it is proposed to provide car-carried apparatus for the use described which is set into operation by an authorized person when the equipped territory is entered, and which acts to initiate an automatic brake application if the engineer fails to perform a suitable acknowledging act at predetermined time intervals, this acknowledgement being required at all times while the vehicle is traveling in an equipped section of trackway, or only under unfavorable traffic conditions, as desired.

Other objects, advantages and characteristic features of the invention will be apparent as the description thereof progresses.

In describing the invention in detail, reference will be made to the accompanying drawings in which:

Fig. 1 illustrates the car-carried equipment embodying the present invention, and also shows the trackway apparatus of a typical train control system of the continuous inductive type;

Fig. 2 is a sectional view of the token lock used in connection with the system of the present invention; and

Fig. 3 shows a modified means for preventing an automatic brake application after a manual brake application is already in effect.

The present invention is applicable to many different types of automatic train control systems and may be used on railways employing different types of trackway apparatus without alteration. The trackway apparatus shown in the drawings is of the type used in connection with an extremely simple automatic train control system of the continuous inductive two-position type, and has been chosen as illustrating one of many types of control systems with which a ve-

hicle equipped in accordance with the present invention may be operated.

Referring to the trackway equipment shown in Fig. 1 of the drawings, the track rails 1 have been shown divided into blocks by the insulating joints 2, the block I and the ends of two adjacent blocks H and J, all being blocks in equipped or train control territory, having been shown. In order to simplify the disclosure, like reference characters having distinctive exponents have been used to designate the corresponding elements of the equipment in the several blocks.

Track relays 3 of the usual direct current type are shown connected across the track rails 1 at the entrance end of each block, and are energized in the usual manner by the track batteries 4, connected across the track rails at the exit end of each block.

Alternating train control current of a suitable frequency is applied to the track rails in series at the exit end of each block through the transformers 5 and 6 from the transmission line 7, the circuit for supplying this current including the contact fingers 8 and 9 and the front contacts of the track relay 3¹ of the next block in advance as shown. It is obvious that the wheels and axles of a train located in a given block will shunt the track circuit and train control currents from the track rails of that block in the rear of the train, causing the de-energization of the track relay 3 at the entrance end of the block and so cutting off the supply of train control current to the track rails of the first block in the rear.

Wayside signals of the color light, semaphore or other suitable type are preferably used in connection with the trackway apparatus of automatic train control systems, and for the purpose of illustration, the semaphore wayside signals Z have been shown in a conventional manner, a disclosure of the operating devices and circuits for these signals being omitted as such apparatus is well known to those skilled in the art and forms no part of the present invention.

Referring now more particularly to the car-carried apparatus comprising the present invention, a railway vehicle has been conventionally represented in the block H by the wheels and axles 10, the normal direction of travel being indicated by the arrow. The vehicle may or may not be provided with inductive receiving coils 11, these coils if provided, being mounted in inductive relation to the track rails ahead of the leading axle of the vehicle.

The car-carried equipment includes the usual engineer's brake valve B. This valve is provided with a suitable actuator for automatic operation, this actuator being of a type now common in train control prac-

tice and being similar to the actuator shown and described in the patent application of Charles S. Bushnell, Serial #712,269, filed May 10, 1924. The actuator comprises in general, two oppositely disposed cylinders, 12 and 13, having pistons therein connected by a rack which engages a pinion or equivalent means on the brake valve stem, the arrangement being such that a difference in air pressure in the two cylinders, 12 and 13, causes the brake valve B to be forced to the application position. This application may be independent of the movement of the brake valve handle or may carry the valve handle to the service position, the engineer being enabled to avoid an automatic application of the brakes in the latter case by holding the handle in its running position. The cylinder 12 is connected directly to main reservoir air pressure, while the cylinder 13 is connected through a pipe 14, a valve V and a second pipe 15 to an electro-pneumatic valve E. P. V. The electro-pneumatic valve E. P. V. is of the type now common in train control practice and operates in a manner which is obvious from the disclosure to connect the pipe 15 to main reservoir air pressure through the chamber 16 when the coil 17 is energized, and to connect the pipe 15 to atmosphere through the chamber 18 and the port 19 when the coil 17 is de-energized.

The valve V comprises a valve seat 20 and a valve member 21, and has two operating positions, the position shown, in which the pipes 14 and 15 are connected, and a position representing a quarter turn of the valve member 21 in a clockwise direction, in which position the pipe 14 is connected to main reservoir air pressure through the port 22. The valve V is operated by a token lock mechanism, representing as a whole as "T" and shown in section in Fig. 2. This mechanism is identical with one form of token lock shown and described in my co-pending application, Serial #42,983, filed July 11th, 1925, and will be only briefly described herein. The valve member 21 is connected to a shaft 23 carrying a disc 24 enclosed within a casing 25. The shaft 23 is provided with an operating handle 26 extending outside of the casing 25 as shown in Fig. 1. The disc 24 has a notch or opening 27 in the peripheral edge thereof, and a lock plunger 28, carried by suitable guides, is adapted to enter the notch 27 and so to lock the disc 24 and the valve member 21 when this member is in the position shown. The plunger 28 is operated by a suitable key which may be removed from the casing when the plunger 28 is in the position shown. When the plunger 28 is withdrawn by the key, and the valve member 21 is turned to a position to connect the pipe 14 and the port 22, the

key is held within the casing 25 by the plunger 28 which is in turn held down by the disc 24. Thus, in order to remove the key, the valve must be in the position shown, and in order to shift the valve, the key must be used to unlock the mechanism and is retained within the mechanism when the valve is in its shifted position.

The repeated acknowledgement at predetermined time intervals is provided for by the use of a clockwork mechanism which operates suitable cams. The shaft 29 carries a pinion 30 engaged by a rack 31. This rack is biased by a spring 32 in such a direction as to tend to turn the shaft 29 in a counterclockwise direction for a limited distance, in the present instance about $1/4$ th of a complete revolution. A ratchet wheel 33 is pinned to the shaft 29 and is engaged by a spring pressed pawl 34, carried by an escapement wheel 35 as shown. The escapement wheel 35 is rotatably mounted on the shaft 29, and its rotation is limited to a predetermined speed by the escapement catch 36. It is evident that as the shaft 29 is wound up, that is, is turned in a clockwise direction in opposition to the pull of the spring 32, the ratchet wheel 33 turns with respect to the escapement wheel 35; and when the shaft 29 is released, the pawl 34 engages the ratchet wheel 33 and the escapement wheel 35 together with its escapement catch 36 acts to retard the turning of the shaft 29.

Two cams, 37 and 38 are secured to the shaft 29. The cam 38 is provided with a notch or depression 39, which is in the position shown when the shaft 29 is wound up. A roller 40, connected to a moveable contact finger 41 bears against the surface of the cam 38, being biased by suitable means to disengage its stationary contact 42 when the roller 40 drops into the notch 39, this occurring when the shaft 29 is in its extreme run down position. The cam 37 is provided with a raised portion 43 adapted to engage a roller 44 to move the contact finger 45 into engagement with its stationary contact 46, this engagement of the contacts 45 and 46 occurring just previous to the engagement of the contacts 41 and 42 in the rotation of the shaft 29. The engagement of the contacts 45 and 46 completes an energizing circuit for a suitable warning device W which may take any suitable form such as a whistle, a bell or a light.

If the receiving coils 11 are used, they are connected to a suitable amplifier, conventionally represented at "Am". This amplifier is of any suitable type adapted to be operated by the voltages induced in the receiving coils 11 and to produce an appreciable current in its output circuit. The output circuit of the amplifier Am. is connected to a suitable magnet 48 having a

pivotal mounted armature 49. The armature 49 carries a latching pawl 50 at a point thereon opposite the shaft 29. At this point on the shaft 29 a ratchet wheel 51 is secured, the arrangement of these parts being such that when the magnet 48 is energized in response to control currents flowing in the track rails, the armature 49 is attracted and the pawl 50 engages the ratchet wheel 51 and thus holds the shaft 29 against rotation 75 in a counterclockwise direction but permitting the shaft to be turned in a clockwise direction.

The resetting or winding up of the shaft 29 is accomplished by means of the acknowledging mechanism designated as a whole as "A". This mechanism comprises a pivotally mounted acknowledging handle 52 connected with a slidably mounted frame 53 having an upturned end 54. The frame 53 carries a pivotally mounted catch lever 55 having a downwardly extending catch portion 56 adapted to engage a stop 57 on the rack 31. The lever 55 is normally biased to the position shown, by the spring 58, connected between the lever 55 and the upturned end 54 of the frame 53. A cylinder 59, shown in cross section, is mounted on the frame 53 and is provided with a piston 60 having a check valve 61 and a leak port 62 therein as shown. The piston 60 is connected by the rod 63 and the link 64 to the lever 55. The cylinder 59 may be filled with a suitable liquid such as oil or it may be an air cylinder as desired. The acknowledging mechanism described acts to prevent the cam mechanism being held in the wound up position by the handle 52 as hereinafter described.

Means may be provided so that the engineer need not operate the acknowledging mechanism "A" at predetermined intervals while the train is at a stop, one method being indicated herein and including suitable contacts which are arranged to be closed when the independent valve of the well-known ET equipment is in its application position. The independent valve handle has been conventionally indicated at 65, and a movable insulated contact 66 has been shown 115 which is operated thereby to engage the stationary contacts 67 and 68, when the valve is in the application position.

Operation

The apparatus of Fig. 1 has been shown in the normal position, that is, with a train proceeding over a section of trackway which is equipped for automatic train control, under clear traffic conditions, and with all 125 circuits and devices properly energized. In order to simplify the disclosure, the letters B and C have been used to designate the opposite terminals of a suitable source of energy, preferably a storage battery.

Considering first the operation of the system shown when no receiving coils, amplifier or latching mechanism are provided, assume that the train while traveling over an unequipped section of trackway, encounters a section which is equipped for automatic train control operation. At this point, the train conductor or other authorized person demands the key or token from the engineer before permitting him to operate the train over the equipped trackway section. In removing the key from the token lock T, the engineer first turns the handle 26 to a position at which the plunger 28 may enter the slot 27 in the disc 24, and in turning the handle to this position, the valve member 21 is turned to connect the pipes 14 and 15. If the train is at a stop when the valve member 21 is so turned, the independent valve handle 65 is in its application position and the contacts 67 and 68 are connected by the moveable contact 66, thus completing an energizing circuit for the electro-pneumatic valve E. P. V. which circuit may be traced as follows:—from the battery terminal B, contacts 66, 67 and 68, wires 70 and 71 and the windings 17 of the valve E. P. V. to the battery terminal C. With the valve E. P. V. energized, main reservoir pressure is supplied to the cylinder 13 and no automatic brake application results.

In order to proceed in the equipped territory, the engineer now operates the acknowledging mechanism A, moving the handle 52 to the right, and so winding up the cam shaft 29 and closing the contacts 41 and 42. An energizing circuit for the electro-pneumatic valve E. P. V. is now completed, which circuit may be traced as follows:—from the battery terminal B, contact finger 41 and stationary contact 42, wires 72 and 71, and the winding 17 of the valve E. P. V. to the battery terminal C. The engineer now releases the engine brakes and proceeds in the equipped territory. After a predetermined time interval, the cam shaft 29 is turned in a counter-clockwise direction by the spring 32, against the retardation of the escapement catch 36, to a position at which the cam 37 closes its associated contacts 45 and 46, thus energizing the warning signal W through a circuit which is obvious from the drawings. The operation of the warning signal W acts to notify the engineer that he must repeat the acknowledging act, that is, must rewind the cam shaft 29 by means of the acknowledging mechanism "A", in order to avoid an automatic brake application. The engineer now operates the acknowledging mechanism "A", thus rewinding the cam shaft 29 as before, and continues to proceed without automatic restriction, this acknowledgment being repeated at predetermined time intervals as

the train proceeds over the equipped trackway section.

If the engineer is incapacitated, asleep, inattentive to the warning signal, or if for any other reason he fails to perform the acknowledging act of rewinding the cam shaft at predetermined intervals, the cam 38 permits the contact finger 41 to disengage its stationary contact 42, thus breaking the energizing circuit to the electro-pneumatic valve E. P. V. which circuit has been traced above. The de-energization of the valve E. P. V. connects the cylinder 13 of the brake valve contactor to atmosphere, and the main reservoir pressure in the cylinder 12 moves the brake valve B to the application position, thus causing a brake application which brings the train to a stop. The engineer may then rewind the cam shaft 29 by means of the acknowledging mechanism "A", release the brakes and proceed by acknowledging at predetermined time intervals as before.

The construction of the acknowledging mechanism "A" is such that the engineer cannot avoid repeated acknowledgment by holding or securing the handle 52 in the right hand or operated position. If the engineer in this manner secures the handle 52 in a position to hold the cam shaft 29 wound up, the spring 32, acting through stop 57 on the rack 31 moves the lever 55, this movement of the lever 55 being opposed by the piston 60 moving to the right in the cylinder 59 as the liquid or air in the cylinder passes through the leak port 62 in this piston. The springs 58 and 32 are so proportioned that the spring 32 overcomes the force exerted on the lever 55 by the spring 58. As the piston 60 moves to the right, the lever 55 turns about its pivot until the catch 56 disengages the stop 57 on the rack 31, thus releasing the rack and permitting the cam shaft 29 to run down. As soon as the catch 56 is free from the rack 31, the spring 58 returns the piston 60 together with the lever 55 to their normal positions as shown, the check valve 61 in the piston 60 permitting the rapid flow of air or liquid from the left to the right of this piston. It is thus apparent that the cam shaft 29 will be released after a time, if the engineer attempts to avoid an automatic brake application by holding the handle 52 to the right. The leak port 62 in the piston 60 is so proportioned that the engineer has sufficient time to properly operate the acknowledging mechanism "A" and rewind the cam shaft 29 before the catch 56 releases the rack 31.

When the train under consideration leaves the equipped territory, the engineer, in order to avoid further acknowledgment, obtains the key or token from the train conductor or other authorized person, un-

locks the token lock T, turns the valve member 21 a quarter turn in a clockwise direction and thus connects the cylinder 13 of the brake valve actuator to main reservoir pressure. The actuator is now rendered inactive as the air pressures in its cylinders 12 and 13 are equal, and the train may proceed in the unequipped territory without automatic restriction regardless of the energization or de-energization of the electro-pneumatic valve E. P. V.

If the receiving coils 11 and the latching mechanism are provided, the engineer need acknowledge only under unfavorable traffic conditions in equipped territory, to avoid an automatic application of the brakes. With this additional equipment, the train control current flowing in the track rails under clear traffic conditions induces voltages in the receiving coils 11, thus causing the energization of the magnet 48 from the output circuit of the amplifier Am. The energization of the magnet 48 lifts the armature 49 and the pawl 50 engages the ratchet wheel 51, thus holding the cam shaft 29 stationary. The cam 38 being held stationary, maintains the contacts 41 and 42 closed and the electro-pneumatic valve E. P. V. is maintained energized, thus permitting the train to proceed under clear traffic conditions without restriction. If the pawl 50 should engage the ratchet wheel 51 when the shaft 29 is in a position to close the contacts 45 and 46, the shaft 29 may be rewound to open these contacts by means of the acknowledging mechanism "A", the pawl 50 permitting the wheel 51 to be turned in a clockwise direction even when the magnet 48 is energized. When no train control currents flow in the track rails, due to the presence of a train, a broken rail or other hazardous condition in the block in which the train under consideration is traveling, or in the first block in advance thereof, the magnet 48 is de-energized, releasing the pawl 50 from the ratchet wheel 51, and permitting the cam shaft 29 to be turned by the spring 32. The engineer must now operate the acknowledging mechanism "A" at predetermined time intervals so long as the unfavorable traffic conditions exist, this operation of the acknowledging mechanism "A" being identical with that described above.

As pointed out above, repeated acknowledgement to prevent an automatic application of the brakes is prevented while the train is standing still by contacts operated in accordance with the position of the independent valve. In Fig. 3, alternative means for accomplishing this result have been shown. This means comprises a simple air switch consisting of a casing 75 having two chambers 76 and 77 separated by a flexible diaphragm 78. The

chamber 77 is connected through the pipe 79 to the brake cylinder pressure of the usual ET equipment and the chamber 76 is open to atmosphere through the port 80. Two insulated contacts 81 and 82 are mounted within the chamber 76, the contact 81 being movable and being connected to the diaphragm 78 as shown, while the contact 82 is stationary. The contact 82 is connected to the battery terminal B, and the contact 81 is connected to the wire 70, the mechanism of Fig. 3 replacing the contacts 66, 67 and 68 shown in Fig. 1. When the train is stationary, the brakes on the engine are held applied, and the air pressure from the engine brake cylinders maintains the contact 81 in engagement with the contact 82 and thus closes an energizing circuit for the electro-pneumatic valve E. P. V., which circuit is obvious from the drawings. It should be noted that if the engineer while proceeding in equipped territory, should initiate a manual brake application, the contacts 81 and 82 are closed to energize the valve E. P. V. and no repeated acknowledgement is required to prevent an automatic brake application so long as the manual brake application is in effect.

It is seen from the description given that an extremely simple and effective means has been devised for maintaining a certain degree of automatic control over the operation of trains not fully provided with train control equipment in trackway sections which are equipped for train control operation. The automobile control provided insures that the engineer is at all times on the alert, is attentive to the signal indications and is aware that he is proceeding in trackway territory which is equipped for train control operation, or in other territory where a certain degree of automatic protection is desired.

As the present invention has been described in connection with a specific form of train control system, and embodies certain specific devices, it should be clearly understood that the invention is not limited in its scope to the specific details and arrangement shown, but that its scope is defined by the appended claims.

What it is desired to secure by Letters Patent is:—

1. In an automatic train control system, car-carried apparatus comprising, a brake applying device acting to apply the vehicle brakes when active, manually operable means for maintaining said device inactive if operated at predetermined time intervals, and a manually operable locking device having a key, said locking device acting to render said brake applying device active when operated to remove said key, and to permit said brake applying device to be rendered inactive when said key is inserted.

2. In an automatic train control system, car-carried apparatus for vehicles traveling over trackway sections not equipped for automatic train control, an automatic brake applying device acting to apply the vehicle brakes when active, a locking device having a key and acting, when operated to permit the removal of the key, to render said brake applying device active for vehicle travel in equipped trackway sections, and manually operable means for maintaining said brake applying device inactive if operated at predetermined time intervals.
3. In an automatic train control system for railways having portions of their trackway equipped for train control operation and portions not so equipped, car-carried apparatus for use on vehicles traveling in said equipped and said unequipped portions of trackway comprising, a normally energized device acting to initiate a brake application when de-energized, manually operable acknowledging means acting if operated at predetermined time intervals to maintain said device energized for vehicle travel in said equipped portions of trackway, and a manually operable locking device acting when operated to render said normally energized device inactive for vehicle travel in said unequipped portions of trackway, said locking device having a key which is retained within said device when operated.
4. In an automatic train control system for railways having portions of their trackway equipped for train control operation and portions not so equipped, car-carried apparatus comprising, a device for causing an automatic brake application when active, a manually operable locking device acting when operated to render said brake applying device inactive for vehicle travel in said unequipped portions of trackway, said locking device having a key which is retained within said device when operated, manually operable means for maintaining said brake applying device inactive for vehicle travel in said equipped portions of trackway if operated at predetermined time intervals, and further means acting to maintain said brake applying device inactive while the vehicle brakes are manually applied.
5. In an automatic train control system for railways having portions of their trackway equipped for train control operation and portions not so equipped, car-carried apparatus comprising, an electro-pneumatic device acting when de-energized to pneumatically operate a brake applying means and thereby initiate a brake application, a manually operable locking device having a key which is retained within said device when said device is in one of its operated positions, said locking device acting to pneumatically disconnect said electro-pneumatic device from said brake applying means

when operated to the position to retain said key, and manually operable acknowledging means for maintaining said electro-pneumatic device energized if operated at predetermined time intervals.

6. In an automatic train control system for railways having portions of their trackway equipped for train control operation and portions not so equipped, car-carried apparatus comprising, an electro-pneumatic device acting when de-energized to pneumatically operate a brake applying means and thereby initiate a brake application, a manually operable locking device having a key which is retained within said device when said device is in one of its operated positions, said locking device acting to pneumatically disconnect said electro-pneumatic device from said brake applying means when operated to the position to retain said key, manually operable acknowledging means for maintaining said electro-pneumatic device energized if operated at predetermined time intervals, and further means for maintaining said electro-pneumatic device energized providing a manual brake application is in effect.

7. In an automatic train control system for railways having portions of their trackway equipped for train control operation and portions not so equipped, car-carried apparatus comprising, an electro-pneumatic device acting when de-energized to pneumatically operate a brake applying means to cause a brake application, a manually operable locking device acting when operated to prevent the pneumatic operation of said brake applying device by said electro-pneumatic device, manually operable acknowledging means acting if operated at predetermined intervals to maintain said electro-pneumatic device energized, and a warning signal associated with the said acknowledging means for indicating said intervals.

8. In an automatic train control system for railways having portions of their trackway equipped for train control operation and portions not so equipped, locomotive apparatus comprising, a train brake applying device having a pneumatic actuator, an electro-pneumatic device connected to said actuator through a manually operable valve and acting when de-energized to operate said actuator and initiate a brake application provided said valve is open, manually operable acknowledging means acting if operated at predetermined time intervals to maintain said electro-pneumatic device energized and thus prevent a brake application while the vehicle is traveling in said equipped portions of trackway, a warning device, for indicating said time intervals, means for maintaining said electro-pneumatic device energized if a manual brake application is in effect on the locomotive, and

a manually operable locking device for locking said valve, said device having a key which is retained therein when said valve is closed for vehicle travel in said unequipped portions of trackway.

5 9. In an automatic train control system, in combination with a device for initiating a brake application when de-energized, means for maintaining said device energized if operated at predetermined time intervals comprising, a shaft biased toward a run-down position, means on said shaft for maintaining an energizing circuit for said device closed until said shaft has turned to said run-down position, and manually operable means for rewinding said shaft, said means acting to release said shaft from the wound-up position if held in such position by said means for more than a predetermined time interval.

10 10. In an automatic train control system, in combination with a device for initiating an automatic brake application when de-energized and manually operable locking means for rendering said device inactive, means for maintaining said device energized if operated at predetermined time intervals comprising a shaft having a retarding mechanism thereon, means for biasing said shaft toward a run-down position, contacts operated in accordance with the position of said shaft and acting to de-energize said device, manually operable winding means for turning said shaft away from said run-down position, said winding means acting to release said shaft if maintained in any but said run-down position for more than a predetermined time interval.

11 11. In an automatic train control system 40 of the type having portions of its trackway equipped for automatic train control and portions not so equipped, trackway means in said equipped portions for transmitting influences continuously to a moving vehicle under favorable traffic conditions only, car-carried apparatus comprising, a device for causing an automatic brake application when de-energized, means for preventing an automatic brake application while the vehicle is traveling in said equipped portions of trackway comprising a manually actuated acknowledging means and a member acting to maintain said device energized when in one position, said member being maintained in said one position so long as said influences are being received from the trackway and being otherwise so maintained by the actuation of the acknowledging means at predetermined time intervals, and means for preventing an automatic brake application while the vehicle is traveling in said unequipped portions of trackway comprising, a manually operable locking means, acting 55 when operated to render said device inactive,

said locking means having a key which is retained therein when operated.

12. In an automatic train control system of the type having portions of its trackway equipped for automatic train control and 70 portions not so equipped, trackway means in said equipped portions for continuously transmitting influences to a moving vehicle under favorable traffic conditions only, and car-carried apparatus comprising, a device 75 acting to initiate an automatic brake application when de-energized, means for maintaining said device energized while the vehicle is traveling in said equipped portions of trackway so long as said influences are 80 being received from the trackway, manually operable means acting to maintain said device energized if operated at predetermined time intervals when no influences are being received from the trackway, manually operable locking means acting when operated to render said device inactive for vehicle travel in said unequipped portions of trackway, said locking means having a key retained 85 therein when so operated, and means for maintaining said device energized so long as a manual brake application is in effect.

13. In an automatic train control system, car-carried apparatus, comprising, a train restricting device operable, when initiated, to cause a train restriction, a manually operable device for preventing initiation of the device if operated at predetermined time intervals, and a locking device operable to make the restricting device ineffective 100 whether or not initiated.

14. In an automatic train control system, car-carried apparatus, comprising, a train restricting device operable, when initiated, to cause a train restriction, a manually operable device for preventing initiation of the device if operated at predetermined time intervals, and a locking device operable to make the restricting device ineffective 105 whether or not initiated, and key means for the locking device, retained in the locking device when it is operated to make the restricting device ineffective.

In testimony whereof I hereby affix my 110 signature.

JAMES A. PEABODY.
